UNITED STATES PATENT OFFICE

168,226

PLASTER MIXER

Daniel C. Jones, Port Washington, Wis., assignor to Kwik-Mix Company, Port Washington, Wis.

Application March 12, 1951, Serial No. 14,464

Term of patent 14 years

(Cl. D14—3)

To all whom it may concern:

Be it known that I, Daniel C. Jones, a citizen of the United States, residing at Port Washington, in the county of Ozaukee and State of Wisconsin, have invented a new, original, and ornamental Design for a Plaster Mixer, of which the following is a specification, reference being had to the accompanying drawing, forming a part hereof, wherein:

The dominant features of my design reside in those portions shown by means of full lines in the drawings.

I claim:

The ornamental design for a plaster mixer, substantially as shown and described.

DANIEL C. JONES.
